CLAIM

The ornamental design for the electric wheelchair as shown and described.

DESCRIPTION

FIG. 1 is a front, top, and right perspective view thereof of an electric wheelchair showing my design;

FIG. 2 is a rear, bottom, and right perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the electric wheelchair and form no part of the claim.
